(57) **CLAIM**

The ornamental design for a marker, as shown and described.

DESCRIPTION

FIG. 1 is a front, right side, top perspective view of a marker showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of the encircled region in FIG. 1; and,

FIG. 9 is a front, right side, top perspective exploded view of the marker showing the various components comprising the marker.

The broken lines depict portions of the marker that form no part of the claimed design. The long dash-short dash broken lines represent the bounds of an enlarged view and form no part of the claimed design.

1 Claim, 9 Drawing Sheets
